(57) **ABSTRACT**

A connector reduced in depth dimension. Contact portions of first and second signal contacts and ground contacts for high-speed transmission are arranged in a housing in a row in a contact arranging direction orthogonal to a fitting/removing direction, and contact portions of contacts for non-high-speed transmission are arranged in the housing in a row in the contact arranging direction below the contact portions of the first and second signal contacts and the ground contacts. Terminal portions of the first and second signal contacts and the ground contacts are arranged in a row in the contact arranging direction, and press-fitting portions of the contracts for non-high-speed transmission are press-fitted in the housing along the direction of height of the housing, whereby they are disposed between the contacts portions and the terminal portions of the first and second signal contacts and the ground contacts.

CONNECTOR

BACKGROUND OF THE INVENTION

1. Field of the Invention

This invention relates to a connector, more particularly to a connector which is reduced in depth dimension.

2. Description of the Related Art

Conventionally, there has been proposed a connector which is provided with a plurality of L-shaped contacts and an insulator holding the contacts, and is mounted on a printed board (see Japanese Laid-Open Patent Publication (Kokai) No. 2002-334748).

The insulator has a fitting portion for fitting to a mating connector. Each L-shaped contact has a contact portion, a held portion, and a terminal portion. The contact portion extends in a fitting direction in which the insulator is fitted to the mating connector. The contact portions are arranged in the fitting portion of the insulator in two rows one above the other in a contact arranging direction. The held portion is continuous with the contact portion, extends in a direction in which the connector is fitted, and is held in the insulator. The terminal portion is soldered to a through hole in the printed board.

In general, the held portion of the L-shaped contact is press-fitted in the insulator along the fitting direction of the connector.

In the connector having L-shaped contacts, the held portions of the contacts extending in the fitting direction of the connector are held by the insulator, and hence it is impossible to obtain a sufficient holding force for holding the held portions of the contacts, unless holding portions of the insulator which hold the held portions of the contacts have a length (in the fitting direction) not shorter than a predetermined length.

In the case of the above-described connector in which the contact portions of the L-shaped contacts are arranged in two rows one above the other, it is necessary to make the length of the held portions of contacts of the upper row longer than that of the held portions of contacts of the lower row, because if the length of the held portions of contacts of the upper row is equal to that of the held portions of contacts of the lower row, the terminal portions of the contacts of the upper row and those of the contacts of the lower row come into contact with each other. Further, the respective lengths of holding portions of the insulator for holding the held portions of the contacts are determined by setting the length of a holding portion of the insulator for holding the held portions of the contacts of the lower row to a reference length as a shortest required length, and hence the length of a holding portion of the insulator for holding the held portions of the contacts of the upper row becomes longer than the reference length. The lengths of holding portions of the insulator are thus determined because if the length of the holding portion of the insulator for holding the held portions of the contacts of the upper row is set to the reference length, the length of the holding portion for holding the held portions of the contacts of the lower row becomes too short to secure a sufficient holding force for holding the contacts.

Therefore, the conventional connector suffers from the problem that the holding portion of the insulator for holding

2

the held portions of the contacts of the upper row becomes long, increasing the depth dimension in the direction of the depth of the connector.

5 SUMMARY OF THE INVENTION

The present invention has been made in view of these circumstances, and an object thereof is to provide a connector which is reduced in depth dimension.

10 To attain the above object, the present invention provides a connector comprising a housing that is capable of being fitted to a mating housing of a mating connector, and a plurality of L-shaped contacts that are held by the housing, the plurality of L-shaped contacts including first contacts and second contacts, wherein each of the first contacts and the second contacts has a contact portion which is capable of being brought into contact with a mating contact of the mating connector, a connection portion which is connected to an object to be connected, and a fixing portion which is fixed to the housing, 15 wherein the contact portions of the first contacts are arranged in at least one row in a contact arranging direction which is orthogonal to a connector fitting direction, wherein the contact portions of the second contacts are arranged in at least one row in the contact arranging direction, wherein the row formed by the contact portions of the first contacts, and the row formed by the contact portions of the second contacts are 20 parallel to each other, wherein the row formed by the contact portions of the first contacts is disposed upward in a direction of height of the housing which is orthogonal to both the connector fitting direction and the contact arranging direction, with respect to the row formed by the contact portions of the second contacts, wherein the connection portions of the first contacts are arranged in at least one row in the contact arranging direction, wherein the connection portions of the second contacts are arranged in at least one row in the contact arranging direction, wherein the row formed by the connection portions of the first contacts and the row formed by the connection portions of the second contacts are 25 parallel to each other, wherein the row formed by the connection portions of the first contacts is disposed rearward in the connector fitting direction with respect to the row formed by the connection portions of the second contacts, and wherein the fixing portions of the second contacts are disposed between the contact portions of the first contacts and the connection portions of the first contacts in the connector fitting direction, and are 30 press-fitted in the housing along the direction of height of the housing.

35 With the arrangement of the connector according to the present invention, the fixing portions of the second contacts are disposed between the contact portions of the first contacts and the connection portions of the first contacts in the connector fitting direction, and are press-fitted in the housing along the direction of height of the housing. This makes it 40 possible to shorten the length of the second contacts in the connector fitting direction, and shorten the length of the first contacts in the connector fitting direction. As a result, the dimension in the direction of depth of the housing is reduced.

45 Preferably, the connection portions of the first contacts each have a planar shape of a surface-mounting type, and the connection portions of the second contacts each have a pin shape of a through hole insertion type.

50 More preferably, the connection portions of the first contacts each protrude out of the housing.

55 55 Preferably, the housing has recesses formed therein, and the second contacts have engaging portions formed for engagement with the recesses, respectively.

Preferably, the first contacts are contacts for high-speed transmission, and the second contacts are contacts for non-high-speed transmission.

More preferably, the contacts for high-speed transmission include pairs of signal contacts for high-speed transmission, and ground contacts for high-speed transmission, and the connection portions of the pairs of signal contacts for high-speed transmission are disposed between the connection portions of ones of the ground contacts for high-speed transmission which are adjacent in the contact arranging direction.

Further preferably, the connection portions of the contacts for non-high-speed transmission are in staggered arrangement in the contact arranging direction.

According to this invention, it is possible to reduce the dimension of the connector in the direction of the depth thereof.

The above and other objects, features and advantages of the present invention will become more apparent from the following detailed description taken in conjunction with the accompanying drawings.

BRIEF DESCRIPTION OF THE DRAWINGS

FIG. 1A is a front view of a connector according to a first embodiment of the present invention;

FIG. 1B is a side view of the connector;

FIG. 1C is a rear view of the connector;

FIG. 1D is a bottom view of the connector;

FIG. 2A is a cross-sectional view taken on line IIA-IIA of FIG. 1C;

FIG. 2B is an expanded view of an S portion appearing in FIG. 2A;

FIG. 3 is a perspective view of an arrangement of contact portions of contacts of the connector shown in FIGS. 1A to 1D;

FIG. 4 is a perspective view of an arrangement of terminal portions of the contacts of the connector shown in FIGS. 1A to 1D;

FIG. 5A is a perspective view of a developed shape of contacts for non-high-speed transmission appearing in FIGS. 1A to 1D;

FIG. 5B is a perspective view of a bent state of the contacts shown in FIG. 5A;

FIG. 5C is a perspective view of the contacts shown in FIG. 5B;

FIG. 6 is a plan view of part of a printed board on which the connector shown in FIGS. 1A to 1D are mounted.

DETAILED DESCRIPTION OF THE PREFERRED EMBODIMENTS

The present invention will now be described in detail with reference to the drawings showing preferred embodiments thereof.

Referring to FIGS. 1A to 2B, a connector 1 is comprised of a housing 3, a plurality of contacts 5, and a shell 7.

The housing 3 is made of a resin having insulation properties. As shown in FIG. 2A, the housing 3 includes a bottom board 31, a rear wall portion 32, side wall portions 33, a holding portion 34, and a projecting portion 35. The bottom board 31 has a plate-like shape, and has a bottom surface formed with a pair of positioning bosses 36. The positioning bosses 36 are inserted in positioning holes 21d of a printed board 21 (object to be connected), shown in FIG. 6. The rear wall portion 32 is continuous with the rear of the bottom board 31. The rear wall portion 32 has a front-side surface (inner surface) thereof formed with a plurality of press-fitting

grooves 32a, and a rear-side surface (outer surface) thereof formed with a plurality of press-fitting grooves 32b, at equally-spaced intervals, respectively. The press-fitting grooves 32a and 32b extend in a direction H of the height of the housing 3 (direction orthogonal to a contract arranging direction C and a fitting/removing direction A). Two side wall portions 33 are continuous with the opposite sides of the rear wall portion 32. The holding portion 34 has a plate-like shape, and is continuous with the rear wall portion 32. The holding portion 34 extends along the fitting/removing direction A (connector fitting direction) in which the housing 3 is fitted in and removed from a mating housing of a mating connector, not shown, and is parallel to the bottom board 31. The holding portion 34 has recesses 34a formed in a lower surface of a front end thereof (see FIG. 2B). The projecting portion 35 is continuous with the rear wall portion 32, both of the side wall portions 33, and the holding portion 34. The projecting portion 35 has a hole 35a formed therein for adjusting the impedance value.

The contact 5 includes contacts (first contacts) for high-speed transmission, and contacts (second contacts) 54, 54' for non-high-speed transmission. The contacts for high-speed transmission includes first signal contacts (signal contacts for high-speed transmission) 51, second signal contacts (signal contacts for high-speed transmission) 52, and ground contacts (ground contacts for high-speed transmission) 53. These contacts 51, 52, and 53 are disposed at predetermined space intervals in the housing 3. The contacts 54 for non-high-speed transmission and the contacts 54' for non-high-speed transmission are alternately arranged in the housing 3 at equally-spaced intervals. One first signal contact 51 and one second signal contact 52 form a pair of signal contacts for high-speed transmission. A pair of signal contacts 51, 52 for high-speed transmission, and one ground contact 53 form one contact group for differential signal transmission.

As shown in FIG. 2A, each first signal contact 51 has a contact portion 51a, a fixing portion 51b, a connecting portion 51c, and a terminal portion (connection portion) 51d, and is formed by blanking and bending a metal plate having elasticity. The contact portions 51a are brought into contact with mating contact portions of mating contacts, not shown. The contact portions 51a are disposed on the upper surface of the holding portion 34. The fixing portion 51b is embedded in the housing 3 by a so-called mold-in method. The connecting portion 51c connects the fixing portion 51b and the terminal portion 51d. The terminal portion 51d is continuous with the connecting portion 51c. The terminal portion 51d has a planar shape of a surface-mounting type and is soldered to a pad 21a (see FIG. 6) on the printed board 21.

The second signal contact 52 has the same shape as the first signal contact 51, and hence reference numerals associated with the second signal contact 52 (52, 52a to 52d) are shown in parentheses beside reference numerals associated with the first signal contact 51 (51, 51a to 51d), and illustration of the second signal contacts 52 is omitted from FIG. 2A. Each second signal contact 52 has a contact portion 52a, a fixing portion 52b, a connecting portion 52c, and a terminal portion (connection portion) 52d, and is formed by blanking and bending a metal plate having elasticity. The contact portions 52a are brought into contact with the mating contact portions of the mating contacts. The contact portions 52a are disposed on the upper surface of the holding portion 34. The fixing portion 52b is embedded in the housing 3 by the so-called mold-in method. The connecting portion 52c connects the fixing portion 52b and the terminal portion 52d. The terminal

portion **52d** is continuous with the connecting portion **52c**. The terminal portion **52d** is soldered to the pad **21a** (see FIG. 6) on the printed board **21**.

The ground contact **53** has the same shape as the first signal contact **51**, and hence reference numerals associated with the ground contact **53** (**53**, **53a** to **53d**) are shown in parentheses beside the reference numerals associated with the first signal contact **51** (**51**, **51a** to **51d**), and illustration of the ground contacts **53** is omitted from FIG. 2. Each ground contact **53** has a contact portion **53a**, a fixing portion **53b**, a connecting portion **53c**, and a terminal portion (connection portion) **53d**, and is formed by blanking and bending a metal plate having elasticity. The contact portions **53a** are brought into contact with mating contact portions of mating contacts. The contact portions **53a** are disposed on the upper surface of the holding portion **34**. The fixing portion **53b** is embedded in the housing **3** by the so-called mold-in method. The connecting portion **53c** connects the fixing portion **53b** and the terminal portion **53d**. The terminal portion **53d** is continuous with the connecting portion **53c**. The terminal portion **53d** is soldered to the pad **21a** (see FIG. 6) on the printed board **21**.

As shown in FIGS. 2A and 2B, each contact **54** for non-high-speed transmission has a contact portion **54a**, a press-fitting portion (fixing portion) **54b**, a connecting portion **54c**, a terminal portion (connection portion) **54d**, an position changing portion **54e**, and a disconnection prevention portion (engaging portion) **54f**. The contact portions **54a** are brought into contact with mating contact portions of mating contacts. The contact portions **54a** are disposed on the lower surface of the holding portion **34**. The press-fitting portion **54b** is press-fitted in a associated one of the press-fitting grooves **32a** of the housing **3**. The connecting portion **54c** connects the contact portion **54a** and the press-fitting portion **54b**. The terminal portion **54d** has a pin shape of a through hole insertion type, and is inserted into a through hole **21b** (see FIG. 6) of the printed board **21**, and is soldered thereto. The position changing portion **54e** connects the press-fitting portion **54b** and the terminal portion **54d**. The position changing portion **54e** is bend rearward, and changes the position (position in the fitting/removing direction A) of the terminal portion **54d** with respect to the press-fitting portion **54b**. The terminal portion **54d** is located rearward of the press-fitting portion **54b**. The disconnection prevention portion **54f** is engaged with an associated one of the recesses **34a** of the holding portion **34**, and is fixed to the holding portion **34** e.g. by an adhesive (see FIG. 2B).

The contact **54'** for non-high-speed transmission has a similar configuration as the contact **54** except an position changing portion **54e'**. The position changing portion **54e'** is folded forward to thereby cause a terminal portion **54d'** to be positioned forward of the press-fitting portion **54b**. As a result, the terminal portions **54d** and **54d'** are in staggered arrangement (see FIG. 4). Therefore, if the terminal portions **54d** and **54d'** are connected by imaginary straight lines, one zigzag line is formed in which mountain-like shapes each in bilateral symmetry are connected in the contact arranging direction C. The terminal portions **54d**, **54d'** are inserted into the respective associated through holes **21b** of the printed board **21**, and are soldered thereto. The through holes **21b** in the printed circuit board **21** are in staggered arrangement matching the staggered arrangement of the terminal portions **54d**, **54d'** (see FIG. 6).

As shown in FIGS. 5A to 5C, the contacts **54** and **54'** are formed by blanking and bending a metal plate having elasticity. The lengths of the contacts **54** and **54'** in the developed

state are equal to each other, which makes it easy to perform bending after blanking. The blanked contacts **54** and **54'** are continuous with a carrier **54g**.

When performing bending, the position changing portion **54e** of the contact **54** is bent in a predetermined direction, and the position changing portion **54e'** of the contact **54'** is bent in an opposite direction to the predetermined direction (see FIG. 5C). Even after bending, the contacts **54** and the contacts **54'** are continuous with the carrier **54g**. This makes it possible to press-fit the contacts **54** and the contacts **54'** in the press-fitting groove **32a** along the direction of the height **H** of the housing **3** at a time. After press-fitting the press-fitting portions **54b**, **54b'** of the contacts **54**, **54'** in the press-fitting groove **32a**, the carrier **54g** is cut off from the contacts **54** and **54'**.

The shell **7** is made of a metal and, as shown in FIGS. 1A to 1D, has leg parts **7a**, contact parts **7b**, and locking pieces **7c**. The leg parts **7a** are soldered to through holes **21c** of the printed board **21** (see FIG. 6), and are grounded. The contact parts **7b** are brought into contact with a mating shell, not shown, of the mating connector via window holes **7d** formed in side walls of the shell **7**. The locking pieces **7c** are disposed within holes **7e** formed in the bottom of the shell **7**. The locking pieces **7c** are engaged with the mating shell of the mating connector, to thereby lock the mating shell to the shell **7**.

As shown in FIG. 3, the contact portions **51a** and **52a** of the first and second signal contacts **51** and **52**, and the contact portions **53a** of the ground contacts **53** are arranged in a row in the contact arranging direction C which is orthogonal to the fitting/removing direction A, respectively.

The contact portions **54a** and **54a'** of the contacts **54** and **54'** are also arranged in a row in the contact arranging direction C.

The row formed by the contact portions **51a** and **52a** of the first and second signal contacts **51** and **52**, and the contact portions **53a** of the ground contacts **53**, and the row formed by the contact portions **54a** and **54a'** of the contacts **54** and **54'** are parallel to each other.

The contact portions **51a** and **52a** of each pair of first and second signal contacts **51** and **52** are disposed between the contact portions **53a** of adjacent ones of the ground contacts **53** in the contact arranging direction C. A pitch of the first and second signal contacts **51** and **52** and the ground contacts **53** in the contact arranging direction C in their row and a pitch of the contacts **54** and **54'** in the contact arranging direction C in their row are different from each other.

As shown in FIG. 4, the terminal portions **51d** and **52d** of the first and second signal contacts **51** and **52**, and the terminal portions **53d** of the ground contacts **53** are arranged in a row in the contact arranging direction C.

The terminal portions **51d** and **52d** of each pair of first and second signal contacts **51** and **52** are disposed between adjacent ones of the terminal portions **53d** of the ground contacts **53** in the contact arranging direction C.

The terminal portions **54d** and **54d'** of the contacts **54** and **54'** are arranged in two rows in the contact arranging direction C. The row formed by the terminal portions **51d** and **52d** of the first and second signal contacts **51** and **52**, and the terminal portions **53d** of the ground contacts **53**, and the two rows formed by the terminal portions **54d** and **54d'** of the contacts **54** and **54'** are parallel to each other. The terminal portions **54d** of the contacts **54** and the terminal portions **54d'** of the contacts **54'**, which form the two rows, are arranged in a staggered manner in the contact arranging direction C. Therefore, if the terminal portions **54d** and **54d'** are connected by imaginary

straight lines, one zigzag line is formed in which mountain-like shapes each in bilateral symmetry are connected in the contact arranging direction C.

As described above, according to the present embodiment, the press-fitting portions **54b**, **54b'** of the contacts **54**, **54'** are disposed between the contact portions **51a**, **52a**, **53a** and the terminal portions **51d**, **52d**, **53d** of the contacts **51**, **52**, **53**, and are press-fitted in the housing **3** along the direction of the height of the housing **3**. Therefore, it is possible to shorten the length of the contacts **54**, **54'** in the fitting/removing direction A, and shorten the length of the contacts **51**, **52**, **53** in the fitting/removing direction A. As a result, the depth dimension of the housing **3** is reduced, and hence the depth dimension of the connector is also reduced.

Further, the contact portions **51a** and **52a** of the first and second signal contacts **51** and **52** for high-speed transmission, and the contact portions **53a** of the ground contacts **53** for high-speed transmission are arranged in a row in the contact arranging direction C, and the contact portions **51a** and **52a** of each pair of first and second signal contacts **51** and **52** are disposed between the contact portions **53a** of the adjacent ground contacts **53** in the contact arranging direction C. This suppresses variation in transmission characteristics or crosstalk between each pair of first and second signal contacts and other pairs of first and second signal contacts, whereby it is possible to prevent degradation in transmission.

Furthermore, the terminal portions **51d** and **52d** of each pair of first and second signal contacts **51** and **52** are disposed between the terminal portions **53d** of adjacent ones of the ground contacts **53** in the contact arranging direction C. This suppresses crosstalk between the terminal portions **51d** and **52d** of each pair of first and second signal contacts **51** and **52**, and the terminal portions **51d** and **52d** of other pairs of first and second signal contacts **51** and **52** which are adjacent thereto, thereby preventing degradation in transmission.

Further, the row formed by the terminal portions **51d** and **52d** of the first and second signal contacts **51** and **52** and the terminal portions **53d** of the ground contacts **53**, and the two rows formed by the terminal portions **54d** and **54d'** of the contacts **54** and **54'** are parallel to each other. This makes it possible to reduce the length of the housing **3** in the contact arranging direction C, and downsize the connector 1. Further, the terminal portions **54d** of the contacts **54** and the terminal portions **54d'** of the contacts **54'** are disposed in staggered arrangement in the contact arranging direction C. This makes it possible to shorten the dimension of part of the printed board **21** where the through holes **21b** are provided, in the arrangement direction p.

Further, the terminal portions **51d**, **52d**, **53d**, **54d**, **54d'** of the contacts **51**, **52**, **53**, **54**, **54'** protrude out of the housing **3**, and hence it possible to easily check the soldered states of the terminal portions **51d**, **52d**, **53d**, **54d**, **54d'**, and easily perform repair of the connector 1.

Further, since the disconnection prevention portions **54f**, **54f'** are secured to the respective associated recesses **34a** of the holding portion **34** of the housing **3**, it is possible to prevent the contact portions **54a**, **54a'** from wobbling.

Although the contacts **51**, **52**, **53** for high-speed transmission are employed as the first contacts, and the contacts **54**, **54'** for non-high-speed transmission are employed as the second contacts, the first contacts are not limited to the contacts for high-speed transmission, and similarly, the second contacts are not limited to the contacts **54**, **54'** for non-high-speed transmission.

Further, although the fixing portions **51b**, **52b**, **53b** of the contacts **51**, **52**, **53** are embedded in the housing **3** by the

so-called mold-in method, the fixing portions **51b**, **52b**, **53b** may be fixed to the housing **3** by press-fitting them into the housing **3**.

Further, although the terminal portions **51d**, **52d**, **53d** for SMT are employed as the connection portions of the contacts **51**, **52**, **53**, the connecting portions of the first contacts may be terminal portions to be inserted into through holed.

Furthermore, although the terminal portions **54d**, **54d'** to be inserted into through holed are employed as the connection portions of the contacts **54**, **54'** for non-high-speed transmission, the connecting portions of the contacts **54**, **54'** may be terminal portions for SMT.

It is further understood by those skilled in the art that the foregoing are the preferred embodiments of the present invention, and that various changes and modification may be made thereto without departing from the spirit and scope thereof.

What is claimed is:

1. A connector comprising:
a housing that is capable of being fitted to a mating housing of a mating connector; and

a plurality of L-shaped contacts that are held by the housing, the plurality of L-shaped contacts including first contacts and second contacts,

wherein each of the first contacts and the second contacts has a contact portion which is capable of being brought into contact with a mating contact of the mating connector, a connection portion which is connected to an object to be connected, and a fixing portion which is fixed to the housing,

wherein the contact portions of the first contacts are arranged in at least one row in a contact arranging direction which is orthogonal to a connector fitting direction, wherein the contact portions of the second contacts are arranged in at least one row in the contact arranging direction,

wherein the row formed by the contact portions of the first contacts and the row formed by the contact portions of the second contacts are parallel to each other,

wherein the row formed by the contact portions of the first contacts is disposed upward in a direction of height of the housing which is orthogonal to both the connector fitting direction and the contact arranging direction, with respect to the row formed by the contact portions of the second contacts,

wherein the connection portions of the first contacts are arranged in at least one row in the contact arranging direction,

wherein the connection portions of the second contacts are arranged in at least one row in the contact arranging direction,

wherein the row formed by the connection portions of the first contacts and the row formed by the connection portions of the second contacts are parallel to each other, wherein the row formed by the connection portions of the first contacts is disposed rearward in the connector fitting direction with respect to the row formed by the connection portions of the second contacts,

wherein the fixing portions of the second contacts are disposed between the contact portions of the first contacts and the connection portions of the first contacts in the connector fitting direction, and are press-fitted in the housing along the direction of height of the housing, and wherein each of the connection portions of the first contacts has a planar shape of a surface-mounting type, and each of the connection portions of the second contacts has a pin shape of a through hole insertion type.

9

2. A connector as claimed in claim 1, wherein each of the connection portions of the first contacts protrudes out of the housing.

3. A connector as claimed in claim 1, wherein the housing has recesses formed therein, and the second contacts have engaging portions formed for engagement with the recesses, respectively.

4. A connector as claimed in claim 2, wherein the housing has recesses formed therein, and the second contacts have engaging portions formed for engagement with the recesses, respectively.

5. A connector as claimed in claim 1, wherein the first contacts are contacts for high-speed transmission, and the second contacts are contacts for non-high-speed transmission.

6. A connector as claimed in claim 2, wherein the first contacts are contacts for high-speed transmission, and the second contacts are contacts for non-high-speed transmission.

7. A connector as claimed in claim 5, wherein the contacts for high-speed transmission include pairs of signal contacts for high-speed transmission, and ground contracts for high-speed transmission, and

10

wherein the connection portions of the pairs of signal contacts for high-speed transmission are disposed between the connection portions of ones of the ground contacts for high-speed transmission which are adjacent in the contact arranging direction.

8. A connector as claimed in claim 6, wherein the contacts for high-speed transmission include pairs of signal contacts for high-speed transmission, and ground contracts for high-speed transmission, and

10 wherein the connection portions of the pairs of signal contacts for high-speed transmission are disposed between the connection portions of ones of the ground contacts for high-speed transmission which are adjacent in the contact arranging direction.

15 9. A connector as claimed in claim 7, wherein the connection portions of the contacts for non-high-speed transmission are in staggered arrangement in the contact arranging direction.

20 10. A connector as claimed in claim 8, wherein the connection portions of the contacts for non-high-speed transmission are in staggered arrangement in the contact arranging direction.
